UNITED STATES PATENT OFFICE

JEREMIAH F. DORGAN, OF BROOKLYN, NEW YORK, ASSIGNOR OF SIXTY-FIVE PER CENT TO MAX RANDALL, OF BROOKLYN, NEW YORK

SPARK INDICATOR FOR INTERNAL-COMBUSTION ENGINES

Application filed October 17, 1927. Serial No. 226,776.

This invention relates to spark indicators for internal combustion engines, and has for its primary object to provide a device of simple construction easily applicable to motor vehicles to provide a positive indication of the presence of a sufficiently high potential for the completion of the spark producing circuit for exploding the charge in the engine cylinders and the proper functioning of the ignition system of the motor when the spark plugs are in operating condition.

More particularly in a practical embodiment of the invention, I propose to provide a plurality of electrically actuated indicating devices, one for each of the motor cylinders suitably mounted and arranged upon the instrument board of the vehicle, and means whereby the excess electrical emanations from the respective spark plugs of the motor may be utilized for the purpose of energizing the indicator actuating devices.

With the above and other objects in view, the invention consists in the improved spark indicator for internal combustion engines, and in the form, construction and relative arrangement of the various parts as will be hereinafter more fully described, illustrated in the accompanying drawings, and subsequently incorporated in the subjoined claims.

In the drawing, wherein I have illustrated one simple and practical embodiment of my present improvements, and in which similar reference characters designate corresponding parts throughout the several views,

Figure 1 is a sectional diagrammatic view showing parts of the motor ignition system and the application of my invention in connection therewith;

Fig. 2 is a detail horizontal sectional view taken substantially on the line 2—2 of Fig. 1;

Fig. 3 is a sectional view taken on the line 3—3 of Fig. 2;

Fig. 4 is a detail perspective view of the collecting means for the electrical current waves, which are disseminated into the atmosphere from the spark plugs of the motor, and

Fig. 5 is a fragmentary front view of the instrument board showing the indicating device thereon.

Referring in detail to the drawings, in which I have more or less diagrammatically illustrated the essential parts of the ignition system, 5 designates a conventional distributor, which distributes the current of high voltage supplied by the usual transformer or coil to the several spark plugs of the motor, one of which is indicated at 6. The spark plugs also may be of the usual type, each plug consisting of an outer metal shell 55 threaded into an opening in the cylinder head and an insulating body of porcelain or other material enclosing the central electrode, one end of which projects into the cylinder and cooperates with a projection from the end 60 of the spark plug shell, said electrode and projection being suitably spaced apart to provide the spark gap across which the current passes to the ground through the cylinder wall. Owing to the very high voltage 65 necessary to create a spark of the desired intensity, there is a considerable discharge of excess current from the other end of the electrode or core of the spark plug. I propose to employ these electrical emanations from 70 the respective spark plugs for the purpose of operating indicating devices mounted on the instrument board of the motor vehicle.

The indicating devices may be of various mechanical forms. As herein shown, I 75 have illustrated a suitable casing or housing 7 fixed upon the face of the instrument board and having a glass front plate 8 secured therein behind which the metal plate 9 is secured within said casing. This metal plate is provided with a plurality of openings 80 10 therein corresponding with the number of the engine cylinders and the face of the plate at one edge of each opening is provided with a suitable index mark indicated 85 at 11.

Upon the opposite side of the instrument board 12, the indicator actuating devices are mounted, each of said devices including a coil 13 of fine insulated copper wire wound 90 upon a soft iron core 14. At one end of this core the permanent magnet 15 is arranged, said magnet and the coil 13, together with said core being supported and arranged within an insulating housing or casing 16. 100

The magnetic action of the magnet 15 on the core 14 causes the opposite end of said core to attract and hold a thin flat spring strip 17 in a normal position, said strip being suitably fixed at one of its ends as at 18 and having its other end extended through an opening in the instrument board 12 and through one of the openings 10 in the plate 9 and provided with an angularly bent finger 19 disposed over the face of said plate. It will therefore, be understood that when the spark plug is not functioning, or no current is being supplied thereto, the finger 19 will be steadily held in line with the index mark 11 of the indicator.

The coil 13 of each indicator actuating device is connected by a wire or other form of conductor 20 with a soft iron disc 21, said discs being suitably mounted upon a slab of insulating material 22 which is mounted and supported in any suitable manner in spaced relation to the outer ends of the spark plugs, and preferably not less than two inches therefrom. The connection of the wires or conductors with the discs 22 may be conveniently made through suitable binding posts 23, the outer ends of said posts and the conductors being enclosed within a conduit or shield 24 of fiber or other suitable material.

It will thus be seen as indicated in Fig. 1 of the drawings that when the high voltage current is transmitted to the spark plug, the excess electrical energy is disseminated from the outer end of the spark plug as indicated at E and is picked up by the soft iron disc 21 and transmitted to the coil 13 by conductor 20. Thus, the coil is charged with alternating current counteracting the magnetic pull of the core 14 and releasing the spring 17 which is normally held under a certain amount of tension, therefore causing the finger 19 at the free end of this spring to be deflected out of registering relation to the index mark 11. Thus, the operator of the vehicle, by noting these regular movements of the indicator fingers 19 with respect to the index marks 11 is afforded a constant indication of the functioning of the ignition system and is instantly aware upon the cessation of such movement of any one of the indicating fingers of the particular spark plug which is not properly functioning. It will be seen that the application of my invention to standard types of motor vehicles requires no connections with either the engine cylinders or the spark plugs or any structural changes in the usual form of the spark plugs. Further, it will be noted that the several parts employed are of exceedingly simple construction so that they may be manufactured and sold at nominal cost and easily applied in operative position on the ordinary motor vehicle.

From the foregoing description considered in connection with the accompanying draw-

ings, the construction, manner of operation and several advantages of my invention will be clearly and fully understood. It will of course, be apparent that if desired, instead of providing an indicating means of the type herein described, separate indicators, each complete in itself for the individual engine cylinders may be mounted and arranged upon the instrument board. Also, instead of mounting and arranging the spring strip 17 to function as the movable element of the indicator, it will be apparent that this spring strip might be caused to actuate a separate indicator member, pivotally or otherwise movable with respect to the indicator plate. Therefore, as to these and other detail variations in the several mechanical parts of my invention as herein referred to, it is to be understood that I reserve the privilege of embodying the same in all such alternative forms as may be fairly incorporated within the spirit and scope of the invention as claimed.

I claim:

1. Spark indicating means for internal combustion engines comprising a visual indicator including a movable element, electrically controlled magnetic means for actuating said movable element, and means for collecting electrical emanations from the spark plug of the engine and transmitting the same to said electrically controlled magnetic means to energize the latter and effect a movement of said indicator element from its normal position, said collecting means being disconnected from the electrical operating circuit of the plug. 90

2. Spark indicating means for internal combustion engines comprising an indicator for each of the engine cylinders, each indicator including a movable element, means magnetically influencing said movable element to hold the same in a normal position, electrically energizable means for disturbing the magnet influence to permit movement of said indicator element from its normal position, and means for collecting electrical emanations from the spark plugs of the respective engine cylinders and transmitting the same to said electrically energizable means of the respective indicators, said collecting means being disconnected from the circuit of each plug. 105

3. Spark indicating means for internal combustion engines including an indicator for each engine cylinder having a resiliently movable element and an indicating member movable thereby with respect to an index mark of the indicator, magnetic means normally holding said resilient element under tension to retain said indicating member in registration with the index mark, electrically energizable means for influencing said holding means to release said resilient element and thereby move said indicating 110 115 120 125 130

member, and means for collecting and transmitting radiant electrical energy supplied to the spark plugs of the engine cylinders to said electrically energizable means of the 5 respective indicators to thereby effect a movement of the indicating member upon each closing of the spark producing circuit, said collecting means being disconnected from the circuit of each plug.

10 4. Spark indicating means for internal combustion engines including an indicating device for each engine cylinder having a movable indicating member and electrically energizable means for effecting movement of 15 said member from a neutral position, a plurality of electrical current collectors insulated from each other and adapted to be arranged in spaced relation to the spark plugs of the respective engine cylinders to 20 collect radiant electrical energy supplied thereto, said collectors being disconnected from the circuit of each plug and conductors connecting the respective collectors with the electrically energizable means of the respective 25 indicators to charge the latter and effect movement of the indicating member upon each closing of the spark forming circuit.

30 In testimony that I claim the foregoing as my invention, I have signed my name hereto.

JEREMIAH F. DORGAN.
